UNITED STATES PATENT OFFICE.

ROBERT ZAHN, OF PLAUEIN, GERMANY.

SHUTTLE EMBROIDERING-MACHINE.

1,088,456.

Specification of Letters Patent. Patented Dec. 23, 1913.

Application filed June 17, 1912. Serial No. 704,106.

To all whom it may concern:

Be it known that I, ROBERT ZAHN, a subject of the German Emperor, residing at Plauen, Kingdom of Saxony, Germany, 5 have invented certain new and useful Improvements in Shuttle Embroidering-Machines, of which the following is a specification.

The construction and arrangement of the 10 shuttle in embroidery machines as in common use for the last thirty years with all the good features have some drawbacks, to which formerly little attention was paid because they were of little import as long as 15 the machines were small, and as long as they were running with slow speed. But now that embroidery machines are built in such enormous sizes as to accommodate about a thousand needles and shuttles and 20 to make about 120 or more stitches per minute, special attention is directed to the question of how to avoid the different defects and to attain the most rapid and uniform work.

25 As one of the seemingly trifling defects may be first mentioned the frequent exchanging and refilling of the shuttles. During the operation of the machine, a great 30 number of attendants constantly have to go up and down to be on the lookout for empty shuttles, and it is evident that with about a thousand shuttles, sufficient attention cannot be given. Therefore, it frequently happens that here and there empty shuttles are 35 not discovered and are left in the machine for some time, the result of which is that the embroidery is faulty, showing lapses. A second defect worth mentioning is waste 40 of thread. The thread in the shuttles is never completely used up and the remnant constitutes waste. Now the more thread a shuttle can take up the less frequently need it be refilled and the waste is proportionately reduced. It would seem that to remove this last named defect it would only be necessary to increase the thread capacity 45 of the shuttle. But by doing it other defects would be entailed. Thus for instance the needle stroke through the embroidery 50 material would have to be enlarged in the measure as the shuttle is made broader. Likewise the loop of the needle thread would have to be increased to allow of the 55 passage of the enlarged shuttle. But just the contrary of that is desirable. For the longer the needle, the thicker must be the

needle shaft and the coarser the needle the less fine can be the embroidery fabric. With coarse needles materials like silk or the like 60 certainly could not be embroidered. A small loop is desired because the larger the same is, the oftener must the needle thread be pulled there and back through the needle eye and stitch hole. The length of thread for a single stitch in proportion to 65 the length of the loop already is considerably small. The frequent pulling there and back of the thread weakens the latter owing to wear. This also is the reason why it is not possible to use fine thread with 70 large shuttles. A further drawback of the old arrangement is that the shuttles being arranged to travel with their covered openings down on the cast iron bed, the narrow bearing edges thereof in course of use become sharp like the blade of a knife, which would cut the thread were the latter allowed to come into contact with the same. To avoid this the needle stroke must be such that the eye of the needle can pass sufficiently far behind the rear sharpened bearing edge of the shuttle. A further objection to the old arrangement is that the cover has to be placed sufficiently deep inside the 75 shuttle and above the bed to make room for the hinge and thread tensioning devices, etc.

The object of my invention is to provide a shuttle having as large a thread capacity as possible and to so arrange the same in the machine that the working conditions between needle and shuttle are in no way affected.

My invention will be more fully understood by reference to the accompanying drawing in which similar reference characters denote corresponding parts and in which—

Figure 1 is a vertical section of my new shuttle showing its position in the machine; Fig. 2 is a longitudinal section thereof; Fig. 3 is a top plan view of the shuttle and Fig. 4 a bottom plan view thereof.

In the drawing *d* denotes the stitch plate which is provided with an opening *i* for each needle *f* and which is fixed to the shuttle bed *c*. The shuttle *a*, except that it is made of as large a size as possible to accommodate a great amount of thread *k* is substantially of ordinary construction. The same is arranged on the bed in such a position that its opening which is closed by the cover *h* is directed toward the stitch plate,

while it movably rests on the bed with one of its solid walls p . By putting the shuttle in such position the enlargement of the shuttle is rendered possible without entailing 5 the above mentioned drawbacks.

With the old construction the rear wall of the shuttle being flat and slanting rearwardly, the needle has to be elongated or given a longer stitching stroke in order that 10 the needle may pass sufficiently far behind the lower edge of said wall to prevent the cutting of the thread by the said edge, which would take place when the edge in course of time sharpens.

With the new arrangement of the shuttle the rear surface n' of the latter is cylindrically curved and forms with the flat solid bottom a blunt edge n , which is located below the body of the shuttle and does 15 not project beyond the rear wall of the latter. By reason of this the needle i without elongation of the needle being required, at the ordinary stitching stroke or even at a shorter stitching stroke will pass sufficiently 20 far beyond said edge n to allow of the thread loop g gently engaging around the curved surface n' of the shuttle. Thus there is no danger of the thread being cut by the edge n . Bearing now with a solid surface 25 30 on the bed instead of with narrow edges the

wear is greatly reduced. Apart from that the new arrangement affords the advantage of quiet work. With the old arrangement the needles had to move in jerks, to rapidly pass in due time the sharp edge of the slanting wall heretofore referred to. With the new arrangement however, the needles can gently move forward and back as there is no sharp edge and therefore no danger of the thread being cut. 35

What I claim and desire to secure by Letters Patent is:

In embroidering machines, the combination with a bed or raceway, the stitch plate, and a stitching needle adapted to reciprocate 40 through said stitch plate and below the raceway, of a shuttle having a curved rear surface, a flat solid bottom bearing on said raceway or bed and its filling opening arranged at the side directed toward the stitch 45 plate, said solid bottom forming with the curved surface a blunt edge located below the body of the shuttle.

In testimony whereof I affix my signature in presence of two witnesses.

ROBERT ZAHN.
